UNITED STATES PATENT OFFICE.

HENRY A. HERR, OF CHICAGO, ILLINOIS.

WORKHOLDER FOR SHAVING OR DRESSING MACHINES.

Application filed March 2, 1923. Serial No. 622,292.

To all whom it may concern:

Be it known that I, HENRY A. HERR, a citizen of the United States, residing at Chicago, in the county of Cook and State of Illinois, have invented certain new and useful Improvements in Workholders for Shaving or Dressing Machines, of which the following is a specification.

This invention relates to improvements in work holders for shaving or dressing machines, particularly adapted though not necessarily limited in its use for shaving or dressing the back of electrotype plates.

Heretofore and in machines of the type embodying a shaving knife or cutter with respect to which the plate is movable, a plate holder has been employed for clamping or holding the plate firmly upon the bed of the machine. These holders are pivotally mounted by one extremity and usually embody a frame having a plurality of rollers extending thereacross and across the plate and adapted to be forced into engagement with the back of the plate and roll thereacross during the dressing or shaving operation.

These rollers being of metal the bodies thereof will not yield, with the result that when pressure is applied to the frame at a considerable distance from the pivot thereof, the back of the frame which is adjacent the cutter will be elevated, thereby releasing the adjacent portion of the plate, while the forward portion of the plate or the part thereof adjacent the point at which the pressure is applied to the frame will be firmly held. This is objectionable as the plate cannot then be trimmed or dressed uniformly and considerable damage and inconvenience will result.

By the use of such a holder two plates of unequal thicknesses cannot be simultaneously dressed or shaved as the thick plate will sustain the holder elevated above the thinner plate and the latter will not be held at all.

To overcome these difficulties and objections and to provide an improved holder of this character having resilient rollers adapted to be forced into engagement with the plate and which will yield to compensate the irregularities of the plate, thereby insuring a proper and firm holding of the plate regardless of the point at which the pressure is applied or the amount of pressure exerted at such point, is one of the objects of the present invention.

A further object is to provide an improved device of this character having means con-

nected therewith for controlling the degree of pressure which may be exerted upon the plate by the holder.

A further object is to provide improved means for guiding or deflecting the chip or shaving removed from the plate by the cutter, thereby preventing the same from interfering with the operation of the cutter or clogging the machine.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention and in which—

Figure 1 is a view in side elevation of a portion of a dressing and shaving machine, having an attachment constructed in accordance with the principles of this invention applied thereto, showing the parts in one position.

Figure 2 is a longitudinal sectional view showing some of the parts in another position.

Figure 3 is a top plan view of Figure 2.

Figure 4 is a perspective view of a detail.

Referring more particularly to the drawings the numeral 10 designates the supporting bed of a dressing or shaving machine having secured thereto a reciprocating plate or carrier 11 upon which the work 12 is adapted to rest. This carrier or support 11 is provided with a stop 13 against which the forward end of the plate engages and the carrier 11 is adapted to be reciprocated in any desired or suitable manner such as by means of racks 14 which are engaged by pinions 15, which latter are rotated in any suitable manner, all as well known in machines of this character.

Mounted upon the supporting structure is a cutter head 16 having a cutter 17 secured thereto and which cutter is secured in position to the head by means of the usual fastening bolts 18, any number of which may be provided.

Interposed between the head of the bolt 18 and the cutter 17 is a washer 19 having an enlarged or thickened portion 20 adjacent the active edge of the cutter, the exposed or outer surface 21 of the portion 20 of the washer is inclined or beveled as shown and the beveled portion terminates adjacent the

active edge of the cutter. The enlarged or thickened portion 20 of the washer forms a shoulder 22, which is disposed below the head 18 of the bolt so that when the cutter 5 removes a chip or portion 23 from the surface of the work 12, as shown in Figure 2, the chip will be deflected away from the head of the bolt 18 and will be prevented from passing under the bolt, which would cause 10 the chip or shaving to become broken and the bolt head would operate as a stop to prevent the chip from passing out of the machine, with the result that the machine would become clogged.

15 Arranged adjacent the cutter head 16 are upright bearing members 24, having slideable bearings 25 mounted therein. Carried by the bottom of each of the bearings is an adjustable stop 26 adapted to engage a stop 20 27 to limit the downward movement of the bearing 25. This movement obviously can be regulated by adjusting the screw or stop 26.

25 A spring 28 is arranged above the bearing 25, one end of which rests upon the bearing and the other end preferably against a plate 29 controlled by a screw 30, and by means of which screw the tension or stress of the spring 28 upon the bearing 25 may be varied. One of these bearings is arranged 30 preferably at each side of the cutter head.

35 A frame like structure 31 is pivotally mounted by one extremity in the bearings 25, and to that end there may be provided a bar or rod 32 connected to the frame and journaled in the bearing.

40 This frame is preferably of a hollow construction, the side members of which converge from the bearings 24 toward the front end of the machine and are connected at such end by means of a cross bar 33. A handle 34 is secured to the cross bar 33 and the side members are preferably of such a length that the handle 34 will project beyond the forward end of the machine so as 45 to permit the handle to be readily grasped by the operator for the purpose of exerting pressure upon the frame 31.

50 A plurality of rollers 35 are journaled to and extend across the frame. These rollers 35 are provided with resilient peripheries and one of the rollers is preferably arranged in close proximity to the cutter 17. With this construction it will be manifest 55 that the frame 31 may be swung about its pivot 32 from the position shown in dotted lines in Figure 1 to the position shown in full lines in said figure, thereby raising the rollers 35 to permit the insertion or removal 60 of the work 12.

65 When the work is placed upon the work support 11 with the forward edge abutting the stop 13, the frame 31 is lowered from the position shown in full lines in Figure 1 to the position shown in dotted lines in Fig-

ure 1 and in full lines in Figure 2, so that the rollers 35 will rest against the back of the work 12. Pressure is then exerted upon the frame by grasping the handle 34 to hold the work firmly upon the work support 11. The peripheries of the rollers 35 being resilient or elastic will compensate any irregularities in the thickness of the plate and it will be manifest that each of the rollers will engage and hold adjacent portions of the plate throughout substantially the entire area of the plate and while the plate is being advanced to the cutter the rollers will roll over the back surface of the plate.

70 The tension of the spring 28 is adjusted so as to hold the roller 35, which is adjacent the cutter 17, against the plate but may yield to permit the bearing 25 to slide in the bearing member 24 to compensate plates of different sizes. That is to say the spring 28 may be so adjusted to permit the holder 31 to accommodate plates of varying thicknesses within certain limits.

75 As a means for holding the frame 31 elevated when the frame is moved into the position shown in full lines in Figure 1, a counterbalancing weight 36 may be provided and this weight 36 is adjustably mounted upon an arm 37, which latter is secured in any suitable manner to the frame 31, and one of these counterbalancing arms 37 may be provided on each side of the machine. The weight 36 serves as a means for assisting 80 in elevating the frame 31.

85 A link 38 is pivotally connected as at 89 with a fixed portion of the machine, preferably to the cutter head 16 and is provided with an elongated slot 40 adjacent its other end. A pin or bolt 41 passes through the slot 40 and is anchored or secured to the arm 37 so that when the frame 31 is moved about its pivot 32, the pin or bolt 41 will slide back and forth in the slot 40, and at the same time the link 38 will move about its pivot 39. This link and bolt and slot connection are provided as a means for controlling or limiting the extent of pressure 95 which may be exerted upon the work 12 when pressure is applied to the handle 34 and is accomplished by reason of the fact that the bolt or pin 41 will engage the end of the slot 40 in the free end of the link and thereby limit the downward movement of the frame 31. As a means for varying the extent of such movement there may be provided an adjustable stop or bolt 42 which is secured to the end of the link 38 and is adapted to be projected into the slot 40 to form an adjustable abutment against which 100 the bolt or pin 41 will strike.

105 After the bolt or stop 42 has once been adjusted such an adjustment will compensate for varying thicknesses of plates or work 110 12 within predetermined limits, as the va-

riation in thickness of the work will be further compensated by the operation of the spring 28 upon the bearing 25. Obviously one of these link attachments may be applied to each side of the frame.

A shield 43 may be provided to extend over the roller 35 and also over the pivot rod 32. This shield may be held in position in any suitable manner preferably by being secured as at 44 to one face of the frame 31 and to that end the intermediate portion of the shield 43 may be cut and deflected as shown in Figure 2.

By use of this shield it will be manifest that when the chip is cut from the work as shown in Figure 2 and is deflected by the beveled portion 20 of the washer 19, the shield 43 cooperating with the beveled surface 20 of the washer will cause the chip to curl over the shield and away from the cutter.

While the preferred form of the invention has been herein shown and described it is to be understood that various changes may be made in the details of construction and in the combination and arrangement of the several parts, within the scope of the claims, without departing from the spirit of this invention.

20 What is claimed as new is:—

1. In combination, a work supporting bed, a cutter beneath which the work is movable, a pressure frame pivotally mounted at one end, a plurality of rollers extending across the frame for engagement with the work, said frame extending for a considerable distance in advance of the cutter and having a hand hold at the free end whereby pressure may be exerted to force the rollers against the work, and a link pivotally anchored at one end and having a loose connection at its other end with the said frame for limiting the movement of the frame under such pressure.

2. In combination, a work supporting bed, a cutter beneath which the work is movable, a pressure frame pivotally mounted at one end, a plurality of rollers extending across the frame for engagement with the work, said frame extending for a considerable distance in advance of the cutter and having a hand hold at the free end whereby pressure may be exerted to force the rollers against the work, a link pivotally connected at one end with the cutter carrier, and a slot and bolt connection between the other end of the link and the said frame whereby the movement of the said frame under such pressure will be limited.

3. In combination, a work supporting bed, a cutter beneath which the work is movable, a pressure frame pivotally mounted at one end, a plurality of rollers extending across the frame for engagement with the work, said frame extending for a considerable dis-

tance in advance of the cutter and having a hand hold at the free end whereby pressure may be exerted to force the rollers against the work, a link pivotally connected at one end with the cutter carrier, a slot and bolt connection between the other end of the link and the said frame whereby the movement of the said frame under such pressure will be limited, and an adjustable stop device projecting into the said slot whereby the extent of such movement may be varied to compensate plates or work of different thicknesses.

4. In combination, a work supporting bed, a cutter beneath which the work is movable, a yieldably mounted bearing adjacent the cutter, a pressure frame pivotally mounted by one end in said bearing, a plurality of rollers journaled in said frame and extending thereacross, said frame extending for a considerable distance in advance of the cutter and having a hand hold at the free end thereof whereby pressure may be exerted upon both of the ends of each of the rollers to force the rollers against the work, and means for limiting the movement of the frame under such pressure, the said means embodying mechanism whereby the extent of such movement may be varied at will.

5. A work supporting bed, a cutter beneath which the work is movable, a movable bearing adjacent the cutter, a spring for controlling the movement of the bearing, means for varying the stress of the spring, a pressure frame pivotally mounted by one end in said bearing, a plurality of rollers having yieldable peripheries, said rollers being journaled to the frame and extending thereacross, said frame extending for considerable distance in advance of the cutter and having a hand hold adjacent its free end whereby pressure may be exerted upon the frame and the outer ends of the rollers to force the rollers into engagement with the work, and a link pivotally anchored at one end and having a loose connection at its other end with the frame for limiting the extent of movement of the said frame under such pressure.

6. A work support, a cutter, a work holding pressure roller adjacent the cutter, means for imparting a relative movement to the cutter and work, and a shield extending over said roller and terminating adjacent the active edge of the cutter for directing the cut material away from the cutter and over the roller.

7. A work support, a cutter, means for imparting a relative movement to the cutter and work, a fastening bolt for the cutter, said bolt projecting beyond the exposed face of the cutter, and means for preventing engagement of the cut material with the bolt and for directing the material away from the said fastening bolt.

8. A work support, a cutter, means for imparting a relative movement to the cutter and work, a fastening bolt for the cutter, said bolt projecting beyond the exposed 5 face of the cutter, a washer disposed between the cutter and the head of the bolt, said washer having a thickened portion adjacent the active edge of the cutter, the outer surface of the thickened portion of 10 the washer being beveled or inclined.
9. As an article of manufacture a washer for use in work shaving or dressing machines having a portion of its body of a thickness considerably less than another portion thereof to form a shoulder extending beyond one face of the washer, the upper surface of the thicker portion being beveled 15 towards one edge of the washer.
10. As an article of manufacture a washer 20 for use in work shaving or dressing machines having a portion of its body of a thickness considerably less than another portion thereof to form a shoulder extending beyond one face of the washer, the upper 25 surface of the thicker portion being beveled towards one edge of the washer, the surface of the washer opposite to the face on which the said shoulder is formed being flat throughout its entire area.
11. In combination, a work supporting 30 bed, a cutter beneath which the work is movable, a pressure frame pivotally mounted by one end and extending for a considerable distance in advance of the cutter, the side 35 walls of the frame converging from the pivot end thereof, a plurality of rollers extending across the frame, the ends of the 40 rollers being journaled in the side members of the frame, a hand hold at the free end of the frame whereby pressure may be exerted upon the rollers to force them against the work, and means adjacent the pivot end of the frame for limiting the movement of the frame under such pressure.
12. In combination, a work supporting 45 bed, a cutter beneath which the work is movable, a pressure frame pivotally mounted by one end and extending for a considerable distance in advance of the cutter, the side 50 walls of the frame converging from the pivot end thereof, a plurality of rollers extending across the frame, the ends of the rollers being journaled in the side members of the frame, a hand hold at the free end of the frame whereby pressure may be exerted 55 upon the rollers to force them against the work, and means adjacent the pivot end of the frame for limiting the movement of the frame under such pressure, the peripheries of the rollers being yieldable.
13. In combination, a work supporting 60 bed, a cutter beneath which the work is movable, a pressure frame mounted by one end for yielding movements in directions toward and away from the bed and for pivotal movement with respect to the bed, said frame extending for a considerable distance in advance of the cutter, a plurality of 65 rollers extending across the frame, the ends of the rollers being journaled in the side members of the frame, a hand hold at the free end of the frame whereby pressure may be exerted upon the rollers to force them against the work, and means adjacent the 70 pivot end of the frame for limiting the movement of the frame under the pressure exerted at the free end of the frame.

In testimony whereof I have signed my name to this specification, on this 23rd day of February, A. D. 1923.

HENRY A. HERR.
